INVENTOR

EARL W. DAVIDSON.
BY
Herbert H. Thompson
his ATTORNEY.

5. This invention relates to radio-receiving apparatus or circuits, and has for its principal objects the production of a receiving set of great sensitivity and, therefore, capable of obtaining a great distance with a minimum number of tubes and also adapted to eliminate the usual disturbing factors interfering with clear, uniform reception. To these ends I prefer to employ an extra electron tube in the radio frequency circuit to connect one side of the coupled inductance to the grids of both tubes, but to connect the plates of the tubes differently, one plate being connected preferably directly to the aerial and the other through a coil of low distributed capacity to the other side of said inductance. I also prefer to place between said coil and the audio frequency output a crystal rectifier for eliminating disturbances and purifying the tone. As an aerial I also prefer to employ a novel type of buried antenna. This consists of a "honey comb" coil impregnated with paraffin or the like and buried in the ground.

Referring to the drawing in which one preferred embodiment of the invention is shown; Fig. 1 is a diagram showing the circuit arrangement I may employ. Fig. 2 is an elevation of my preferred form of underground antenna. Fig. 3 is a similar view of the preferred form of aerial for my circuit. Fig. 4 is a sectional view on an enlarged scale of the central insulator used in Fig. 3. In Fig. 1, 1 represents any form of antenna, 2 the usual variable condenser, 3 a loose coupler or coupled-inductance, the primary 4 thereof being connected to condenser 2 and to the ground G. Preferably I place a high resistance 5, say one megohm around said condenser 2. My two detector tubes are shown at 6 and 7, and the circuit is of the regenerative or feed back type. Preferably I connect the grids 8 and 9 of both tubes to one part (preferably the primary 4) of the coupler through a grid leak 22 and grid condenser 23, while the plate 10 of tube 7 is connected to a mid-part or tap in a self-inductance coil 11. Said coil is preferably of low distributed capacity for which the honey comb type is suitable. The secondary 4' of

the coupler 3 is also connected to the first turn of said coil 11, while the last turn of said coil is carried to the ground through variable resistance 12 and also to the output represented diagrammatically at 15, it being understood that I can employ any type of audio frequency amplification if desired.

The plate 10' of tube 6 I connect to the aerial as shown. The filaments or electron discharge devices are lighted in the usual manner from "A" battery 13 and one side thereof is also connected back to the primary 4 of coupler 3 for regenerative action. The secondary 4' of the coupler is connected through variable resistance 14 to one side of the output 15, the other side of the output being connected in the usual manner to the B battery 16 and to A battery 13. I also prefer to place a crystal 17, which may be similar to the usual crystal rectifier or detector and which is preferably of the pressure type, such as iron pyrites, in the circuit in such a manner as to feed a small amount of audio frequency current to the crystal where it is met by the radio-frequency current, thus making a very sensitive circuit as well as making more volume of sound. To this end the crystal is shown as placed between the aforesaid coil 11 and the output 15, with the direct connection from secondary 4' shunted therearound through resistance 14 placed toward the audio frequency side. This has been found by actual trial to have a very beneficial action in cutting out "static" and increasing the selectivity (both primary and secondary) and in combination with the honey comb coil 11 and special type of aerial described below gives a reception which is clear even under the most adverse conditions, such as caused by the northern lights or an approaching storm without the sacrifice of distance.

Regarding the increased sensitivity which I am able to obtain by my invention, I have as yet formed no theory but it may be by reason of inter-regenerative action between the tubes.

As stated hereinbefore, my preferred type of aerial for my circuit is a buried inductance coil 20 (Fig. 2). This coil is preferably of

the compact high inductance, low-distributed capacity type such as the honey comb or lattice work coil. Preferably I completely enclose the coil in paraffin 21 or other moisture-proof insulating material and bring both ends to the surface of the ground, either end being connected to my receiving circuit.

In Figs. 3 and 4 I show another excellent form of aerial for use in my circuit. This 10 antenna is made in the form of an X, with wires 25 and 26 joined at the top by wire 27 and crossed through separated holes 28 and 29 in an insulator 30. It is shown as supported at the top by "A" frame 31 and insulators 33, 33 and 34 and at the bottom by a similar frame 35 and insulators, and is normally supported vertically on brackets 36.

In accordance with the provisions of the patent statutes, I have herein described the 20 principle and operation of my invention, together with the apparatus which I now consider to represent the best embodiment thereof, but I desire to have it understood that the apparatus shown is only illustrative and 25 that the invention can be carried out by other means. Also, while it is designed to use the various features and elements in the combination and relations described, some of these may be altered and others omitted without 30 interfering with the more general results outlined, and the invention extends to such use.

Having described my invention, what I claim and desire to secure by Letters Patent is:

35 1. A radio receiving circuit comprising the combination with an aerial, a coupler, and an inductance, of a plurality of electron tubes having the grids thereof connected to one side of the coupler, the plate of one tube connected to the aerial and the plate of the other tube connected to a tap in said inductance, said inductance being connected at one end to the secondary of said coupler and at the other end to the ground and to the output.

40 2. A radio receiving circuit comprising the combination with an aerial, a coupler, and an inductance, of a plurality of electron tubes having the grids thereof connected to one side of the coupler, the plate of one tube connected to the aerial and the plate of the other tube connected to a tap in said inductance, said inductance being connected at one end to the secondary of said coupler and at the other end to the ground and to the output,

45 3. A radio receiving circuit comprising the combination with a honey comb coil aerial buried in the ground, a coupler, and an inductance, of a plurality of electron tubes having the grids thereof connected to one side of the coupler, the plate of one tube connected to the aerial and the plate of the other tube connected to a tap in said inductance, said inductance being connected at one end to the sec-

ondary of said coupler and at the other end to the ground and to the output.

4. A radio receiving circuit comprising the combination with an aerial, a coupler, and an inductance, of a plurality of three element electron tubes having the grid of each connected to one side of the coupler, the plate of one tube connected to the aerial, and the plate of the other tube connected to a tap in said inductance, said inductance being connected at one end to the secondary of said coupler and at the other end to the ground and to the output.

5. In a radio receiving circuit, the combination with the aerial, a plurality of thermionic tubes having the grids thereof connected to the input, a tapped self-inductance coil connected at a midpoint to the plate of one tube, a coupler connected to one end of said coil, an output circuit connected to said coupler, and a crystal connected between the other end of said coil and the output.

In testimony whereof I have affixed my signature

EARL W. DAVIDSON.
